NONREFILLABLE ATTACHMENT

Jacob W. Schieber, Scranton, Pa.

Application October 29, 1936, Serial No. 108,287

3 Claims. (Cl. 215—22)

This invention relates to a non-refillable attachment for bottles, jugs and containers, and is designed primarily for use in connection with bottles containing high grade liquors, wines, perfumes, etc., but it is to be understood that the attachment, in accordance with this invention, may be employed in connection with any type of container, holding powder or pellets, for which it is found applicable.

10 The object of the invention is to provide, in a manner as hereinafter set forth, an attachment of the class referred to which, when in anchored position with respect to a bottle, will prevent the surreptitious refilling of the bottle after the original contents of the latter have been discharged.

15 A further object of the invention is to provide, in a manner as hereinafter set forth, an attachment, for the purpose referred to, which will permit a steady discharge, with no surging action, 20 of the contents of a bottle when the latter is tilted from the vertical to beyond the horizontal, and further will prevent discharge from the bottle when the latter is disposed in a vertical inverted position.

25 Further objects of the invention are to provide, in a manner as hereinafter set forth, a non-refillable attachment for bottles, jugs and containers which is simple in its construction and arrangement, readily installed with respect to the 30 neck of a bottle, jug or container, strong, durable, compact, thoroughly efficient in the use intended thereby and comparatively inexpensive.

With the foregoing and other objects in view, the invention consists of the novel construction, 35 combination and arrangement of parts as will be hereinafter more specifically described and as are illustrated in the accompanying drawing wherein is shown an embodiment of the invention, but it is to be understood that changes, variations and 40 modifications may be resorted to which fall within the scope of the invention as claimed.

In the drawing:—

Figure 1 is an elevation of the attachment installed with respect to the neck of a bottle,

45 Figure 2 is a vertical sectional view of the attachment installed with respect to a bottle,

Figures 3, 4, 5 and 6 are, respectively, sections on lines 3—3, 4—4, 5—5 and 6—6, Figure 1,

Figure 7 is a top plan view of the combined 50 valve seat and intake member for the valve chamber,

Figure 8 is a top plan view of the combined sealing and retaining element,

Figure 9 is a longitudinal sectional view of the 55 attachment free of the bottle neck, and

Figure 10 is a modified form of attachment.

With reference to Figures 1 to 6, both inclusive, the attachment is generally indicated at 12 and it includes a hollow body part 13 of cylindrical 60 cross section. The body part 13 has an outer

terminal part 14 of reduced outer diameter with respect to the remaining part 15 thereof. The part 14 is tubular, of less length than part 15 and constitutes a neck for receiving a closure 16 in the form of a cork. The part 14 also functions as a discharge outlet for the contents of the bottle 17 and an air intake as indicated at 14a, when the contents of the bottle are being discharged.

5 The breast and neck of bottle 17 are indicated at 18, 19 respectively. The neck 19 intermediate its ends is formed with an annular stop bead or flange 20 on its outer periphery. That portion of the neck extending outwardly from bead 20 is of reduced thickness, as at 21 and is provided with threads 22 on its outer periphery.

10 The body part 13 has parts of different uniform inner diameters as indicated at 23, 24, 25 and 26 and a portion 21 of gradually decreasing diameter outwardly. The part 24 is of greatest inner diameter and it is interposed between parts 23, 20 25. The latter is of smaller inner diameter than part 23. The part 25 is of greater diameter than part 26. The part 23 is of greater length than parts 24 and 25. The parts 24, 25 are substantially of the same length. The part 26 is of 25 greater length than part 23. The part 27 is of greater length than part 26 and the greatest diameter thereof corresponds to the diameter of part 25. The junction of the parts 23, 24, 25 and 26 form the body part 13 with internal annular shoulders 28, 29 and 30.

15 The part 23 is threaded and is at the inner terminal portion of the part 15 and provides the body part 13 with an internally threaded annular coupler 31 for encompassing and connecting the 35 body part 13 to the reduced portion 21 of the neck 19 of the bottle.

The shoulders 28, 29 coact with the parts 24 to 40 form body part 13 with an internal annular groove immediately forward of the part 23. The parts 26, 27 coact to form body part 13 with an internal valve chamber 32 having its rear portion of 45 uniform diameter and its forward portion of frusto-conoidal contour. The chamber 32 is closed at its forward end and open at its rear end.

The body part 13 is formed therein with a pair of oppositely disposed inwardly inclined openings 33, 34 constituting outlets for chamber 32. There is provided in body part 13, lengthwise of the latter a pair of spaced oppositely disposed tortuous tubular conducting passages 35, 36 which are closed at their inner ends and open at their forward ends into combined discharge outlet and air intake provided by the tubular part 14. The passages 35, 36 forwardly of their closed ends 50 permanently communicate with the outlets 33, 34 respectively for the chamber 32.

55 Formed integral with and of less length than that of the part 26, which forms the rear portion of uniform diameter of the valve chamber 60

- 32, is a series of inwardly extending spaced ribs 37 disposed lengthwise with respect to the valve chamber. The ribs 37 are of less length than and are flush with the inner edge of part 26.
- 5 Positioned against the shoulder 30 and against the inner end of the ribs 37 is a combined valve seat forming and intake member 38 in the form of an annulus and which has its outer edge abut part 25.
- 10 Arranged within the annular groove provided by the shoulders 28, 29 and part 24 is a combined sealing and retaining element 39 in the form of a resilient annulus 40 which bears against the shoulder 29, part 24, the rear face of member 38 and retains the latter in position. The inner and outer diameters of annulus 40 are greater than that of member 38. When element 39 is in sealing and retaining position, it is mounted on and extends outwardly from the edge of the bottle neck 19.
- 15 Prior to the coupling or connecting the attachment to the bottle neck, the threads of the latter, as well as the threads of the coupling 31 are coated with cementitious material 41 possessing a characteristic when set to secure the attachment and bottle neck together in a manner to prevent the separation of one from the other without breakage.
- 20 Arranged within the valve chamber 32 is a pair of superimposed valves 42, 43. Valve 42 is globular and valve 43 of disc-like form. Valve 42 constitutes a weighting means for and seats on valve 43. The latter is formed of resilient material. The valve 43, when in body part 12, is surrounded by the ribs 37.
- 25 When the attachment is set up, two like oppositely disposed body part sections are provided corresponding to the sections shown in Figures 2 and 9. These sections are formed of a material which will permit of connecting them together by fusing, brazing or welding to form an integral body. Prior to connecting the sections together, the valves, member 38 and element 39 are positioned within the sections. The body part 13 has 30 an uninterrupted smooth outer periphery.
- 30 The modification shown in Figure 10 will be of the same construction as the attachment shown in Figure 1, with this exception, that the modification indicated at 44 will be formed with a corrugated outer periphery.
- 35 If the bottle is tilted with respect to the horizontal to the right, the passage 35 constitutes a fluid discharge passage and the passage 36 provides a combined fluid discharge and air intake passage. If the attachment is tilted with respect to the horizontal to the left, then the passage 36 forms a fluid discharge passage and the passage 35 provides a combined fluid discharge and air intake.
- 40 The parts of the attachment are so arranged to provide for discharge of the contents of the bottle after the attachment is disposed at an angle with respect to the horizontal and as the attachment, when extending downwardly, is moved 45 towards the vertical, the flow decreases and completely stops when the attachment assumes an inverted vertical position. It is thought that the preventing of discharge from the bottle, when the attachment is in an inverted position and 50 vertically disposed, is due to an air-trap effect within the attachment. The tubular tortuous passages are of like form, oppositely disposed,
- 55 having offset closed branches and so formed as to prevent the passage of a wire or other implement to hold valve 36 off of its seat to sur- 60 repititiously refill the bottle.
- The attachment is for employment in connection with any form of container having a neck or an annular extended intake or filling member. The term container is also meant to imply a bottle or a jug. The term neck is also meant to imply an annular extended intake or filling member.
- 65 What I claim is:
1. A non-refillable attachment for containers of the neck type comprising respectively a tubular structure provided with means to provide respectively an internally threaded annular coupler for connecting it to the neck of the container; an internal annular groove forwardly of the outer end of the coupling; an internal annular shoulder forwardly of the groove; a valve chamber having a closed forward end, an open rear end and a rear portion of uniform diameter merging into the free end of said shoulder; a pair of spaced oppositely disposed outlets for said chamber; an opening at its outer end for receiving a removable closure and providing when the closure is removed a fluid discharge outlet and an air intake; a pair of spaced tubular conducting passages having closed rear ends and their outer ends merging into said opening; said passages communicating forwardly of their closed ends with said outlets; and inwardly extending spaced ribs integral with that portion of uniform diameter of said chamber and constituting valve guides, a combined sealing and retaining element mounted in said groove and for seating on the neck of the container when the attachment is coupled to said neck, a combined valve seat forming and intake member for said chamber interposed between said shoulder and element, said element and said member being in the form of an annulus, a disc-like valve mounted on said member and encompassed by said ribs, and a globular valve mounted on and constituting a weighting means for the said other valve.
2. The invention as set forth in claim 1 having the inner and outer diameter of the sealing and retaining element greater than that of the combined valve seat forming and intake member, and said element being formed of resilient material of greater outer diameter than the edge of the neck of the container.
3. In a non-refillable attachment for containers of the neck type, a structure for connection to and for extension from the container neck, said structure being formed with means to provide respectively a valve chamber intermediate its ends with the chamber open at its inner end, an annular shoulder at the inner end of said chamber, spaced ribs integral with the rear portion of the wall of said chamber; a combined outlet and inlet and a pair of tubular conducting-off passages communicating with said chamber and opening into said combined outlet and inlet, a combined sealing and retaining element seated within said structure and in the form of an annulus, a valve seat forming and intake member interposed between said shoulder and element and in the form of an annulus, and a pair of superimposed valves in said chamber and one being mounted on said member and surrounded by said ribs.
